JOHANNES C. L. VAN DER LANDE, OF UBBERGEN, NETHERLANDS, ASSIGNOR TO OEL-WERKE NOURY & VAN DER LANDE OF EMMERICH, GERMANY

APPARATUS FOR AUTOMATICALLY COVERING THE BASINS OF PRESSES AND THE LIKE

Application filed February 25, 1929, Serial No. 342,636, and in the Netherlands March 3, 1928.

This invention relates to improvements in oil presses and more particularly to a novel means whereby the oil basins may be covered to prevent pollution of the oil.

In filling presses, for example oil presses with the materials to be pressed, these presses having either rising or fixed basins for the oil, the difficulty is often experienced, that a part of said material falls into said basin, owing to which the oil which later on will flow into these basins, is seriously polluted.

To clarify this oil again so as to make it useful for practice, expensive installations are necessary.

The apparatus according to the present invention now eliminates these drawbacks for the greater part and guarantees that an oil is obtained which is nearly free from any press-material.

It is characterized by the feature that the fixed or rising basins of the oil-presses are associated with an apparatus, in such a way, that said basins are covered while the material to be pressed is being brought into the presses, but are automatically opened again as soon as the machine starts to press, so that the oil pressed out of the material may flow into said basins and at the same time the waste press-material is put outside the press.

The invention will now further be explained by reference to the accompanying drawings, it being understood that various changes may be made in the form, construction, size and arrangement of the component parts of the invention without departing from the nature and principle of the invention:

Fig. 1 is a vertical sectional view of the invention embodied in a covering for fixed oil basins.

Fig. 2 is a top plan view of the structure shown in Fig. 1.

Fig. 3 is a view similar to Fig. 1, showing the invention embodied in a covering for rising oil basins.

Fig. 4 is a top plan view of the structure shown in Fig. 3.

In the embodiment shown in Figs. 1 and 2, the plates 1 rest on the fixed oil basins 6, the latter surrounding the oil-press, said plates,

at the outer side of the basins, being mounted for vertical swinging movement by means of hinges 5, and covering the basins as much as possible.

On said plates 1, in a well known manner, levers 2 are mounted which can slide over pins 4, upon which they rest or are mounted in such a way that they may have such motion; these pins 4 are mounted in a stamp 7 which rests upon the rising and lowering cylinder 9. If this stamp 7 is raised, which stamp together with cylinder 9 is a part of the oil-press, so that the pressing of the material begins, the levers 2 sliding over the pins 4 are elevated and owing to this movement of the levers, the plates 1 are lifted up at the inner side of the press, so that the waste press-material slides off, the basins are uncovered and the oil can flow into the basins.

Also at the highest position of stamp 7 at which the levers 2 are nearly vertical, the levers which still rest on the pins 4 are supported thereupon in such a manner that, the pressing being finished and the stamp 7 lowered, they again assume their horizontal position and the plates 1 again cover the basins and new material can be brought into the press-plates mounted between the columns 8 of the press, the oil being supplied to the basins without being polluted.

In case of oil-presses having basins which are raised during pressing, the plates 1 in Figs. 3 and 4 are provided with levers 2 to the outer ends of which chains 3 are connected. These chains are connected at their inner ends to a common weight 11, which at the lowest position of the presses rests on a foot-stall 10.

When the basins are raised and the pressing begins, the weight 11 becomes free, whereupon the chains 3 are stretched, levers 2 are drawn downwards and the plates 1 upon which these levers are mounted and which, just as in case of the plates for the fixed basins, may, for example by means of hinges 5, be mounted for vertical swinging movement on the outer sides of the basins, assume a vertical position, whereupon the

waste press-material slides off and the oil can flow into the uncovered basins.

In any form of apparatus according to the invention the plates cover the basins around the columns 8, which are a part of the press, as completely as possible and are preferably in two pieces.

It is clear that the apparatus according to the invention is not restricted to use on oil-presses only, but may be installed on all similar machines.

What I claim is:

1. In an oil press or the like embodying a basin means for covering the basin to prevent pollution of the contents of the basin comprising a cover plate movable into and out of position to cover and close the basin, and means automatically actuated through operation of a moving part of the press for effecting such movement of the plate.
2. In an oil press or the like embodying a basin, means for covering the basin to prevent pollution of the contents of the basin comprising a cover plate movable into and out of position to cover and close the basin, and tending to assume its closed position by gravity, and comprising, also, means for supporting the plate during its period of movement from closed to open and from open to closed position.
3. In an oil press or the like embodying a basin, means for covering the basin to prevent pollution of the contents of the basin comprising a cover plate, a hinged member supporting the plate for movement into and out of position to cover and close the basin, and means, carried by a vertically movable part of the press, engaging beneath the hinged member for effecting such movement of the plate.

In testimony whereof I have signed my name to this specification.

JOHANNES C. L. VAN DER LANDE.
